ASSEMBLING MACHINE

Nelson H. Mageoch, Westfield, N. J., assignor to
 Western Electric Company, Incorporated, New
 York, N. Y., a corporation of New York

Application July 25, 1944, Serial No. 546,561

5 Claims. (Cl. 91—44)

1

This invention relates to assembling machines, and more particularly to machines for assembling crystal units.

In the manufacture of certain types of quartz crystal units, the crystal is enclosed in a housing and it is important that the housing as well as the crystal be freed of moisture.

An object of the invention is to provide an assembling machine which is highly efficient and practical for use in assembling articles into units.

With this and other objects in view, the invention comprises an assembling machine having a support to move articles to be assembled in a given path, means for use in assembling certain of the articles with connecting members to form units thereof, and means actuated at given intervals to deposit a sealing material on the connecting members.

Other objects and advantages will be apparent from the following detailed description when considered in conjunction with the accompanying drawings, wherein

Fig. 1 is a top plan view of the machine, portions thereof being broken away;

Fig. 2 is a side elevational view of the machine, portions thereof being broken away;

Fig. 3 is an enlarged vertical sectional view of a portion of the machine, illustrating the depositing of the sealing material on the connecting members or screws of the units;

Fig. 4 is an enlarged fragmentary detailed view taken along the line 4—4 of Fig. 1, and

Fig. 5 is a fragmentary detailed sectional view taken substantially along the line 5—5 of Fig. 3.

Referring now to the drawings, attention is first directed to Fig. 1, which illustrates a support or turret 10 movable about its axis at a given low speed, approximately one revolution every half hour, to move units formed of the articles, namely casings 11 (Fig. 4) and their covers 12, at spaced locations in the given circular path. These articles are moved through an oven 14 in which a series of heating lamps 15 are disposed to heat the articles and to drive off all moisture therefrom. This result is accomplished although the units are partially assembled manually prior to their entering the oven by placing the covers upon their respective casings and positioning retaining members, such as screws 16 (Figs. 3 and 5), in the apertures provided therefor in the articles. Sealing washers 17 space the articles apart so that moisture may be driven from the inside of the casings 11.

Through the aid of an air-driven screw driver unit 18, the screws 16, there being two in num-

ber for each unit, may be simultaneously driven until the covers for each unit are uniformly secured in place. The units remain at fixed positions upon the support 10 and continue their travel toward and past a sealing unit 19, where, under the control of each unit, means is actuated to cause ejection of quantities of sealing material 20 (Fig. 3) to be forced or caused to drop into the apertures over the screws 16.

Considering now the specific structure of the machine, attention is directed to Fig. 2, which illustrates a frame 22 supporting the remaining structure of the machine including an electric motor 23 which drives a speed reducing unit 24, an output shaft 25 of which has a pinion 26 mounted thereon. The pinion 26 drives a bevelled gear 27, which is fixedly mounted upon a vertical shaft 28, the latter being supported by a bearing bracket 29. A pinion 30, fixed to or formed integral with the shaft 28, drives a ring gear 31, which is fixed to the under surface of the support 10, to thus move the support at a given speed about its axis. The support 10 has an integral hollow cylindrical portion 33 which serves as a hollow shaft rotatable about a vertical stationary hollow shaft or structure 34, the latter being fixed in any suitable manner to the frame 22. A table 36 is mounted upon the fixed shaft 34 and assists in supporting the upper structure of the machine.

The oven 14 is supported by suitable brackets 38 and 39 and is provided with suitable insulating material as indicated at 40. The oven is also formed to receive the articles 11 and 12 for their movement into, through and out of the oven.

The screw driver unit 18 is supported as illustrated in Figs. 1 and 2, and may be of any desired structure including screw driver elements 42 disposed at given positions corresponding to the spaced positions of the screws 16 and driven by air under pressure or other suitable power means. The detailed structure of the unit 18 will not be specifically shown or defined, as it is to be claimed generally. The screw driver unit 18 is supported by a bent pipe or tubular member 44 supplied with air under pressure from a supply line 43 connected to the screw driver unit through lines 46 and 47. The screw driver unit includes a hose portion 48 flexible so that the head 49 supporting the screw driver elements 42 may be moved to the necessary positions during the continuous movement of the support 10.

The sealing unit 19 supported by the fixed hollow shaft 34 extends outwardly therefrom

to a position above the articles on the support 10. The outer end of the unit 18 includes a housing 45 having a cover 46 therefor hingedly mounted at 47. A receptacle 48 is disposed in the housing 45 and extends through an aperture 49 in a bottom wall 50 of the housing. Two jets or nozzles 51 of the cross-sectional contour illustrated in Fig. 3 extend through apertures in the bottom wall of the receptacle 48 and are provided with vertical apertures or passageways 52 and horizontal passageways 53. The upper portions of the vertical passageways 52 are enlarged to receive valves 55, which are normally held closed, to close both apertures 52 and 53 by the aid of springs 56. The springs 56 are disposed concentric with the valve stems 57, which extend vertically into guides 58, the latter being integral portions of a cover 59 of the receptacle. Collars 60, mounted upon their respective valve stems 57 and fixed thereto, are disposed beneath the springs 56 and receive the forces therefrom to hold their respective valves 55 closed.

A flat plate 62, apertured to receive reduced upper ends 63 of the nozzles or jets 51, is held in place by the aid of a bolt 64 and is only slightly larger in width than the diameter of the reduced portions 63, so that the opposing sides of the receptacle 48, which is cylindrical in cross-section, may be free for the passage of sealing material 20 to pass therethrough. The sealing material is not shown in Fig. 3 other than the deposits thereof in the apertures over the heads of the screws or connecting members 16, but it should be assumed that the receptacle 48 may be substantially filled with the sealing material, which in the present instance is a suitable lacquer. The cover 59 is normally held closed through the aid of thumb screws 66 and may be removed from the receptacle by the opening of the cover 46 of the housing 45, so that the sealing material may be disposed within the receptacle.

The power means for opening the valves 55 includes a solenoid 68 mounted in the housing 45 and including a core 69 pivotally connected at 70 to an actuating member 71. The member 71 is pivotally supported at 72, the latter being carried by a vertical frame 73. The frame 73 has outwardly projecting integral portions 74 which carry variable stop screws 75 and 76, the latter having helical springs 77 disposed concentric therewith for a purpose hereinafter described. An arm 79 is integral with the actuating member 71 and is positioned between the upper stops 75 and 76, the former governing the normal position of the actuating member, while the latter limits the actuating movement of the member, the adjacent spring in turn serving to normally hold the arm in engagement with its respective stop screw 75. A latch 81 is pivotally connected at 82 to the actuating member 71 and is normally urged counterclockwise by a spring 83. A tooth 84 of the latch 81 is positioned to engage a companion tooth 85 of an actuating element 86, the latter having its adjacent end mounted upon the pivot 72. The element 86 is provided with an arm 88 integral therewith and extending between the lower stop screws 75 and 76 and controlled thereby as well as by the adjacent spring 77. The outer end of the element 86 is bifurcated, as at 90, to straddle a connecting rod 91 which extends through a bushing 92 in the cover 59. A lateral member 93, carried by the inner end of the rod 91, is apertured for the valve stems 57 and supports the collars 60 thereof. Suitable washers 95

serve to seal the bushing 92 when the rod 91 is in its uppermost position. A threaded member 96, disposed upon a threaded portion 97 of the rod 91, is engaged by the bifurcated end 98 of the element 86 to provide connection between the element and the rod.

Through this connection energization of the solenoid 68 will move the actuating member 71 counterclockwise to move the actuating element 86, through the connection of the latch 81, in the same direction, to move the rod 91 upwardly and with it the valves 55. The amount of movement imparted to the rod may be determined through the positioning of the threaded member 96. During this upward movement of the valves, a pin 100, carried by the latch 81, rides upon a cam 101 to cause the latch to be freed of the actuating element 86 at a given position and thus disconnect the actuating elements from the actuating member 71 and allow the valves 55 to be closed.

The sealing material in the receptacle 48 is forced in given quantities through the jets 51 by the application of air under pressure to the supply of the material in the receptacle. Air is supplied to the receptacle from the supply line 43, through the pipe line 44, through a line 103 which includes a pressure reducing valve 104, and into the upper end of the receptacle 48. Thus with the constant application of air under pressure to the sealing material, or with its application at given intervals, the valves 55 need to be opened only momentarily.

The control for the actuation of the valves 55 and the energization of the solenoid 68 extends to the units formed by the articles 11 and 12 and located on the support 10. In other words, a switch 108, mounted in the housing 45 and of the normally open type actuated into closed position by a spring actuated plunger 109, is included in an electrical circuit (not shown) to cause energization of the solenoid when closed. An arm 110, positioned in engagement with the plunger 109, is normally held against a stop 111 by the force of a spring 112. The arm 110 is fixedly mounted upon a vertical shaft 114, which extends downwardly through a bearing 115 (Fig. 3) fixedly mounted in an aperture of the base or bottom portion 50 of the housing 45. An enlarged portion 116 of the shaft 114 carries a resilient arm 117, bent at its outer end, as at 118 (Fig. 5), to provide a rounded portion positioned to be engaged by the units as they move successively on the table into the finishing position beneath the unit 18. The arm 117 is positioned so that when actuated by one of the units to cause rotation of the shaft 114 against the force of the spring 112, to cause the arm 110 to actuate the plunger 109 to close the switch 108 and thus cause energization of the solenoid 68, resulting in the opening of the valves 55, the unit, which caused this train of action, will be disposed with the screws or connecting members 16 in direct alignment with the jets 51, to receive the quantities of the sealing material 20 therefrom.

Considering now the operation of the machine, the articles 11 and 12 are alternately disposed upon the support 10 at a position indicated generally at 120 (Fig. 1). In viewing Fig. 4, it will be noted that spacers 121 are mounted like distances apart on the support to receive the articles 11 and 12 in alternate positions therebetween. As previously described, the article 11 is in the form of a casing, while the article 12 in the present embodiment is a cover therefor including hollow terminals 122. To further describe the cover 12,

supporting wires (not shown) are fixedly mounted in the hollow terminals 122 and have a crystal secured to their ends.

The operation of the machine is completely automatic through the area adjacent the unit 19, where the assembled articles or units remaining upon the support 10 successively engage the resilient arm 117 (Figs. 3 and 5). The arm 117 when actuated causes closing of the switch 109 to energize the solenoid 68 and thus cause actuation of the member 71 and, through the latch 81, actuation of the element 86, to move the valves 55 upwardly free of their seats and to open communication between the passageways 53 and 52 of the jets, so that the pressure upon the sealing material in the receptacle 48 may cause given quantities of the material to be forced through these apertures in the jets and into the apertures of the covers or articles 12 provided for the screws or connecting members 16. The valves 55 are held open momentarily until the latch 81 is tripped by the cam 101, allowing the springs 56 to return the valves 55 to their closed positions. The springs 77 also function to return their respective actuating member 71 and element 86 to their normal positions, in which connection is again formed therebetween through the aid of the latch 81.

It will, therefore, be observed that through the continuous rotation of the support 10 resulting from the energization of the motor 23 and its driving connection through to the ring gear 31, the completed units may be removed from the support after they pass the unit 19 and a new supply of articles 11 and 12 may be alternately disposed upon the support to travel through the oven 14 to be partially assembled at 128, and, through the aid of the unit 18, this assembly may be completed by the sealing of the connecting members as they pass between the unit 19.

Although specific improvements of the invention have been shown and described, it will be understood that they are but illustrative and that various modifications may be made therein without departing from the scope and spirit of this invention as defined by the appended claims.

What is claimed is:

1. In an assembling machine, a continuously rotatable support having a circular portion adjacent its periphery to support units formed of casings and covers therefor joined by threaded members disposed in apertures of the casings and covers, and to move them in a circular path, a container for a sealing material, a nozzle disposed over the path of the threaded members, and means to cause quantities of the material to pass through the nozzle and into the apertures of the covers over the threaded members.

2. In an assembling machine, a continuously rotatable support having a circular portion adjacent its periphery to support units formed of casings and covers therefor joined by threaded members disposed in apertures of the casings and covers, and to move them in a circular path, 65 spacing members on the support adjacent the periphery thereof to space the units like distances apart, a container for a sealing material, a nozzle disposed over the path of the threaded members, and means actuatable by the units as they successively approach the nozzle to cause 70 quantities of the material to pass through the

nozzle and into the apertures of the cover over the threaded members.

3. In an assembling machine, a continuously rotatable support having a circular portion adjacent its periphery to support units formed of casings and covers therefor joined by threaded members disposed in apertures of the casings and covers, and to move them in a circular path, spacing members on the support adjacent the periphery thereof to space the units like distances apart, a container for a sealing material, a nozzle disposed over the path of the threaded members, means actuatable by the units as they successively approach the nozzle to cause quantities of the material to pass through the nozzle and into the apertures of the cover over the threaded members, and means actuatable to vary the quantities of the material passed through the nozzle.

4. In an assembling machine, a continuously rotatable support having a circular portion adjacent its periphery to support units formed of casings and covers therefor joined by threaded members disposed in apertures of the casings and covers, and to move them in a circular path, spacing members on the support adjacent the periphery thereof to space the units like distances apart, a container for a sealing material, a nozzle disposed over the path of the threaded members, a valve normally closing the nozzle operable into open position, and means operable by the units as they successively approach the nozzle to cause operation of the valve to cause quantities of the material to pass through the nozzle and into the apertures of the cover over the threaded members.

5. In an assembling machine, a continuously rotatable support having a circular portion adjacent its periphery to support units formed of casings and covers therefor joined by threaded members disposed in apertures of the casings and covers, and to move them in a circular path, spacing members on the support adjacent the periphery thereof to space the units like distances apart, a container for a sealing material, a nozzle disposed over the path of the threaded members, a valve normally closing the nozzle operable into open position, a solenoid energizable to operate the valve to successively free quantities of the material to pass through the nozzle and into the apertures of the cover over the threaded members, and a switch in an electrical circuit, including the solenoid, successively actuated into closed position by the units.
